UNITED STATES PATENT OFFICE

123,705

DESIGN FOR A LONG RANGE BOMBER MONOPLANE

Aristede A. Theodoropoulos, New Haven, Conn.

Application January 11, 1940, Serial No. 89,389

Term of patent 3½ years

To all whom it may concern:

Be it known that I, Aristede A. Theodoropoulos, a citizen of the United States, residing in New Haven, in the county of New Haven and State of Connecticut, have invented a new, original, and ornamental Design for a Long Range Bomber Monoplane, of which the following is a specification, reference being had to the accompanying drawings, forming part thereof, in which

Fig. 1 is a top plan view of a long range bomber monoplane showing my new design;

Fig. 2 is a front elevational view of the said monoplane design;

Fig. 3 is an enlarged side elevational view of said monoplane design;

Fig. 4 is an enlarged bottom plan view of said monoplane design, and

Fig. 5 is a sectional view on line 5—5 of Fig. 1.

I claim:

The ornamental design for a long range bomber monoplane, substantially as shown.

ARISTEDE A. THEODOROPULOS.
